US0D1054996S

(12) **United States Design Patent** (10) **Patent No.:** **US D1,054,996 S**
(45) **Date of Patent:** **** Dec. 24, 2024**

(54) **POWER STRIP**

(71) Applicant: **Deals Realm LLC**, Eastvale, CA (US)

(72) Inventor: **Yuebo Tao**, Guangdong (CN)

(73) Assignee: **Deals Realm LLC**

(**) Term: **15 Years**

(21) Appl. No.: **29/886,051**

(22) Filed: **Mar. 3, 2023**

(30) **Foreign Application Priority Data**

Sep. 6, 2022 (CN) 202230588610.3

(51) **LOC (14) Cl.** **13-03**

(52) **U.S. Cl.**

USPC **D13/139.8; D13/137.2**

(57) **CLAIM**

The ornamental design for a power strip as shown and described.

DESCRIPTION

FIG. 1 is a front, right and top perspective view of a power strip, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan view thereof.

The broken lines depict portions of the power strip that form no part of the claimed design.

1 Claim, 8 Drawing Sheets
